PLUG SEALING MEANS FOR METALLIC CONTAINERS

Louis B. Wackman, St. Louis, Mo., assignor to
American Flange & Manufacturing Co., Inc.,
Chicago, Ill., a corporation of Illinois

Application February 6, 1929, Serial No. 337,815

2 Claims. (Cl. 220—39)

This invention relates to an improvement in a plug sealing means for metallic containers and the like and has for its primary object the purpose of providing a means of obstruction which must be destroyed for removal of the plug from the bushing of the container before the contents of the container can be removed.

Another object of the invention is to provide a plug sealing means for the closure plug of a container for obstructing undetectable access to the plug for the removal thereof.

A further object of the invention is to provide a sealing means for the closure plug of a container in the form of a cap which is adapted to cover the closure plug and the bushing in which the plug is secured and the bushing provided with means which are cooperable with the cap for securing the cap thereto.

Other and further objects will appear in the specification and be specifically pointed out in the appended claims, reference being had in the accompanying drawing, exemplifying the invention, and in which:—

Figure 1 is a view illustrating the invention as applied to the plug and bushing and showing the bushing secured in the wall of a metallic container, a portion of the container wall being shown in section.

Figure 2 is a plan view partly in section taken approximately on the line II—II of Fig. 1.

Figure 3 is a transverse vertical section taken on the line III—III of Fig. 2.

Referring by numerals to the accompanying drawing 1 designates a wall of a metallic container such as is used in oil shipping, and formed in said wall as a counter-sunk portion 2 forming an embossment and formed concentrically in the portion 2 is an opening 3 having a surrounding depending neck or flange 4.

Mounted in the neck 4 is an interiorly threaded portion 5 of a bushing 6, said bushing having a horizontally disposed flange 7 which is seated on the gasket 8 in the counter-sunk portion 2 and extending circumferentially around the flange 7 is a vertical wall or edge 9 having an outwardly disposed annular bead or lip 10. The bushing 6 is held in the neck 4 of the wall 1 by the outwardly flared portion 11 which underengages the lower edge 12 of the neck 4, the annular extremity 13 of the flared portion 11 being curled against the outside of the neck 4.

For closing the container, a closure plug 14 having circumferential wrench engaging means 15 and socket wrench engaging means 16, is engaged in the threaded portion 5 of the bushing 6.

the flange portion 17 of said plug being engaged against the gasket 18 which engages against the flange 7 of the bushing 6. The greatest diameter of the flange 17 of the plug 14 is much less than the inside diameter of the bushing 6 provided across the wall 9, thereby providing an annular space or gap around the flat-sided circumferential wrench engaging means 15 of the flange 17 of the plug 14, for permitting overengaging of a socket wrench with the plug.

When a container is filled for shipment and the closure plug 14 is secured in the bushing 6 as shown in Fig. 3, and it is desired to provide a seal for the plug, a cover cap 19 having a depending skirt 20 is mounted on the annular wall 9 of the bushing 6 and the skirt 20 of the cap will overengage the annular lip 10 as shown in Fig. 3. While pressure is brought to bear on the cap 19 to hold it against the upper edge of the wall 9, a tooling implement is operated on the skirt 20 of the cap for forcing said skirt in underengagement with the annular lip 10 of the wall 9 of the bushing 6, this operation being the sealing operation for securing the cover cap to the bushing.

The cover cap 19 is preferably made of a light weight material such as a thin sheet metal which will readily break or tear in tampering in the event that an unauthorized person attempts to pry or move the cover cap from the annular lip 10, and in the event of any such tampering the same can be readily detected by the receiver of the container after shipment to the receiver has been made.

In the lawful operation of opening the container for drawing the contents, a dislodging tool can be used for under-engaging and prying the bent edge of the skirt 20 of the cap from under-engagement with the lip 10 of the bushing 6 for removing the cover cap 19 and providing accessibility to the plug 14 for wrench engagement for removing the plug from the bushing 6.

By the provision of both the circumferential wrench engaging means 15 and the socket wrench engaging means 16 on the plug 14, two forms of wrenching tools may be used, for in some instances, the plug 14 may be secured so tightly in the bushing that a wrench engaged in the socket 16 cannot permit enough force to be applied to the plug for loosening it. The provision of the circumferential wrench engaging means 15 will therefore permit an over-engaging wrench to be applied to the plug by reason of the annular space between the flange 17 of the plug and the wall 9 of the bushing, the

application of the over-engaging wrench permitting greater leverage being applied to the plug for loosening.

Obviously constructional modifications of the device are possible without departing from the spirit of the present invention and therefore it is to be understood that it is not necessary to limit the invention by the terms used in the foregoing description, excepting such as the state of 10 the art may require.

What I claim is:—

1. A fitting for a container comprising a bushing having an interiorly threaded part and an annular wall disposed outwardly of the threads 5 of said part, said wall having a laterally extending annular lip on its extending end, a plug cooperable with said threaded part of the bushing having its top wall disposed on a plane inwardly of the lip and its wrenching end spaced 15 from said annular wall for permitting wrench engagement over the perimeter of the wrench-

ing end of the plug, and a cap having a skirt mounted over the extending end of said annular wall and having its skirt contracted over the lip.

2. A fitting for a container comprising a bushing having an interiorly threaded part and an integral annular wall disposed outwardly of the threads of said part, said wall having a laterally extending annular lip formed on the outside thereof at its upper end, a plug cooperable with 10 said threaded part having its top wall disposed below the lip of the annular wall and its wrenching end disposed within the confines of said annular wall and spaced therefrom for permitting wrench engagement over the perimeter of the 15 wrenching end of the plug, and a cap having a skirt mounted over the upper end of said annular wall and having its skirt clinched over said lip.

LOUIS B. WACKMAN. 20
